UNITED STATES PATENT OFFICE.

JAMES HOWARD MCLELLAN, OF VANCOUVER, BRITISH COLUMBIA, CANADA.

DRINK-DISPENSING MACHINE.

Application filed July 6, 1925. Serial No. 41,721.

My invention relates to improvements in drink dispensing machines which has for its particular objects the filling of a cup and the delivery of the cup when filled, and for the disposition of a further cup in position for filling subsequent to the insertion of a coin into a slot in the machine.

The invention consists essentially of a supply tank, a cup cage and means for feeding the cups into filling position behind a closable pair of doors and as each cup is filled for opening the doors and thrusting the filled cup into delivery position, as will be more fully described in the following specification, in which:

Fig. 1 is a side view of my invention.

Figure 1^A is an enlarged view of the cup carrier actuating clutch.

Fig. 2 is a longitudinal section showing the valve operating cam and the door operating mechanism.

Figure 2^A is a sectional view of one of the dash pots.

Fig. 3 is a plan view taken below the cup cage and feed ring.

Fig. 4 is a fragmentary side view showing the driving mechanism.

Fig. 5 is a transverse section looking towards the delivery recess.

Fig. 6 is a fragmentary section showing the cup carrier.

Fig. 7 is a fragmentary view of the cup arm spreader.

Fig. 8 is a fragmentary section showing the feed valve operating mechanism.

Figure 9 is a side view of the invention showing the parts in the position assumed during operation.

Figure 10 is a transverse sectional view of the cup carrier mechanism taken on the line 5-5 of Figure 3.

Figure 11 is an enlarged view of the cup carrier ring.

Figure 12 is a front view of the cup delivery recess showing the filled cup just released by the cup carrier.

Figure 13 is a sectional view taken through the cup carrier ring showing the manner in which the rim of the lowermost cup is pressed downwardly to release it from the cup next above it.

In the drawings like characters of reference indicate corresponding parts in each figure.

55 The numerals 1 and 2 indicate longitudi-

nal frame members which are mounted upon a suitable base and are connected together by transverse members 3 and 4. On the rear end of the frame members 1 and 2 a supply tank 5 is carried which is in communication with a feed tank 6 through a supply pipe 7 and a valve 8 having a delivery spout 9. Adjacent the front end of the frame members 1 and 2 is a pair of standards 10 connected together by a transverse member 11 which carries a column 12 having a circular threaded head 13 and supported upon the standards 10 is an annular ring 14 having an internal thread 14^A which corresponds with and runs parallel to the thread of the head 13. The distance between the inside of these threads is equal to the diameter of the rim of the cups used in the machine so the cups may be carried by their rims upon the threads and must pass completely around between the ring and the head before they are permitted to fall into filling position. The cups which are nested in columns are deposited in pockets 15 in a rotatable cage 15^A mounted upon a vertical shaft 16 which extends through the column 12 and is provided at its lower end with a mitre pinion 17 driven by a corresponding gear 18 on the shaft 19. The nested cups which are usually of pressed and waxed paper are apt to stick together and as a means for disconnecting the lowermost cup from the one immediately above it, the leaving end of the thread 14^A of the annular ring 14 is sharply curved downwards as at 20, and immediately above this downward curve is an enlargement 20^A on the underside of the thread 14^A forming a wedge which is adapted to enter between the rim of the lowermost cup and that of the cup next above it, to disrupt the adhesion caused by the nesting of the cups.

The thread of the head 13 stops at a point previous to the leaving end 20 of the thread 14^A as at 21, so as to leave no support for the cup rim adjacent the head when the cup is in position to fall, but I provide a segment 22 pivotally mounted upon the column 12 which is adapted to lie in substantial contact with the leaving end 21, of the thread to carry the cup rim. This segment is held by gravity in normal lowered position as shown in Figure 1 by means of the push rod 23, the cranks 24 and 25 and the arm 26 on the clutch collar 69.

The numeral 27 indicates a channel through which the coin, by which the machine is operated, is adapted to fall, this channel is formed of a plurality of fixed sections, one pivotally mounted section 28 and a normally contracted section 29 having a pivotally mounted side groove 30 which is adapted to be swung outwardly at a predetermined period of operation to drop the coin into a suitable receptacle. The numeral 31 indicates a further coin channel (shown in dotted lines in Figure 1 and in full line in Figure 5). A cup when in position to be filled rests upon the inner end of a cranked arm 32, which when depressed by its weight holds the channel section 28 in alignment with the channel 27 so that the coin is allowed to fall into the normally contracted section 29 to close an electric circuit by which the machine is operated, but if no cup is delivered to the cranked arm 32 the counterweight 33 raises the inner end of the arm 32 and through a connecting rod 34, shown in dotted lines in Figure 5, swings the section 28 outwards to discharge the coin from the channel 27 into the channel 31 whence it is returned into a suitable receiver accessible to the person who sought to use the machine. The two parts forming the section 29 are each suitably connected to wires with which the motor 35 is in circuit.

The numeral 36 indicates the main shaft upon which is keyed adjacent the frame member 1, a driving crank 37, see Figure 4, having an inverted T-shaped rocker 38 mounted at its outer end. One leg of the rocker is provided with a dog 39 which is adapted to be held in contact with a ratchet wheel 40 by a tension spring 41 secured to the boss of the crank 37. The opposite end of the rocker is pointed as at 42 and is adapted to engage a notch 43 in a plate 44 mounted on a flat spring 45 secured to the crank, and the centre leg 46 of the rocker is adapted to strike the adjustable stud 47 of the lug 48 to disconnect the drive of the crank 37 through the rocker 38 from the ratchet wheel 40 and reversely when striking the adjustable stud 49 of the lug 50 to disengage the pointed end 42 of the rocker from the plate 44 to reinstate the driving connection.

The ratchet wheel 40 is freely rotatable upon the shaft and is attached to a worm wheel 51 which is driven by a worm 52 on the motor shaft 53. Therefore each operation of the motor will rock the shaft 36 through an arc prescribed between the studs 49 and 47 and by providing a weight arm 54 upon the shaft when such movement is completed the dog 39 will lift, allowing the shaft to rock back to its starting position as shown. As the dog 39 is lifted the pointed end 42 of the rocker is brought into engagement with the notch 43 in which it is held until the centre leg 46 is brought into con-

tact with the stud 49 which action frees the rocker 38 and allows it to return to engaging position with the ratchet wheel 40. Adjacent the opposite end of the main shaft 36 is a crank 55, its outer end being operated by a tension spring 56 shown partly in dotted line in Figure 1, which serves to accelerate the rocking of the shaft back to its normal position.

The numeral 57 indicates a crank having at its outer end a crank pin 58 and at a point closer to the main shaft 36 a boss 59 through which a sliding connecting rod 60 has movement. This connecting rod is provided with a stop collar 61 to prevent its movement through the boss 59 in a forward direction beyond a predetermined point and at the outer end of the rod a pin 62 is provided from which a tension spring 63 extends to the boss 59 of the crank 57. The opposite end of the connecting rod is coupled to an outwardly spring pressed plunger 64 of a dash pot 65 of any suitable type which is adjusted to accomplish the outward movement of its plunger in a predetermined period and to make its inward movement quickly. In this case there is sufficient time to allow a cup to be filled through the valve spout 9. The operation of said valve will be hereinafter described.

The numeral 66 indicates a substantially horizontal crank extending forward from the main shaft 36 and having a pin 67 at its outer end which when the crank descends on the forward movement of the main shaft, thrusts back the arm 68 fulcrumed to the base of the frame member 2 and latches temporarily thereon as at 69. The numeral 70 indicates a drive clutch disc of any suitable type having as many points of engagement as there are columns of cups in the cage and which is mounted on the shaft 19 to drive the cup cage 15^A through the mitre pinions 18 and 17 and the vertical shaft 16.

The numeral 71 indicates a clutch ring having suitable pawls for imparting rotation to the clutch disc. Extending from the clutch ring is a crank 72 which in turn is coupled by a connecting rod 73 to the pin 58 of the crank 57 so that the forward movement of the main shaft and the crank 57 through these connecting parts imparts rotation to the cup cage 15^A to carry another column of nested cups over the filling position and to release the lowermost cup from the one next above. The pin 26 projecting from the periphery of the clutch ring 71, when returning to normal position, as shown in Figure 1 engages the crank 25 to lower the segment 22, thus withdrawing support from the portion of the rim of the lowermost cup adjacent the column 12.

This cup having been detached from the one next above it by the wedging action produced by its engagement with the thread 130

enlargement 20^a is then free to drop into filling position.

The numeral 75 indicates a tension spring through which the forward movement is imparted through a crank 76 to a shaft 77. This movement is delayed until the plunger 64 is fully returned into the dash pot 65 when the pin 62 at the end of the connecting rod 60 comes into engagement with the lever 78 on the stub shaft 79 and withdraws the stop 80 from the end of a further crank 81 on the shaft 77. A crank 82 on the shaft 77 is coupled by a rod 83 having a sliding movement through the bent over outer end 10 of the arm 68 and having an adjustable nut 84 at its outer end, serves to release the pin 67 of the arm 66 to permit the main shaft 36 to return to normal position.

The numeral 85 indicates a crank extending rearwardly of the frame from the main shaft 36 and having a roller 86 at its outer end which is adapted to be resiliently engaged by a substantially triangular shaped cam 87 secured upon the shaft 77 so that, as the crank 85 is raised, the shaft 77 is permitted to be rocked by the spring 75 in a forward direction, and as it descends, is rocked in an opposite direction. The numeral 88 indicates a dash pot which through 25 its connecting rod 89 and a crank 90 is adapted to permit a quick forward and a slow return rocking movement to the shaft 77.

The numeral 91 indicates a crank upon the shaft 71 which through a short connecting rod 92 imparts a reciprocating movement to the plunger 93 of the cup delivery mechanism which will be dealt with later. Upon the inner end of the stub shaft 79 a crank 94, see Figures 1 and 3, is mounted, which actuates a push rod 95 which is adapted to bear during the latter part of its stroke, upon a crank 96 mounted upon a horizontal shaft 97 to withdraw a pair of locking dogs 98 from corresponding recesses in the doors 99 at the rear of the delivery recess 100. A connecting rod 101 couples the outer end of the crank 94 to a short crank 102 secured to a short shaft 103 and journaled upon the 40 top of the frame member 2, which shaft carries an arm 105 which is adapted when actuated to depress the outer end of the valve plunger push rod 107, see Figure 8.

Journaled above the transverse member 3 45 is a bell crank 106 having a rockingly mounted push rod 107 connected to the upper end of its vertical leg 108. The horizontal leg 109 of the bell crank 106 is adapted to bear upon a sliding pin 110 extending through the member 3, which pin is actuated by a cam 111 secured to the shaft 36. The valve 8 consists of a cylindrical casing 112 into which the supply pipe 7 leads adjacent one end. A port 113 (shown in dotted line 50 in Figure 3) communicates with the feed

tank 6 and an outlet port 114 adjacent the opposite end communicates with the spout 9.

The numeral 115 indicates a piston having a piston rod 116, the end of which is normally engaged by one end of the push rod 70 107. The piston is pressed outwards to normal position between the port 113 from the feed tank and the port 114 to the spout 9, by a spring 117, so that as the cam 111 raises the pin 110 and through the bell 75 crank 106 and push rod 107 drives the piston rod 116 inwards, the piston 115 is disposed between the port 113 to the feed tank and the supply pipe 7, so as to permit the liquid which had flowed into the feed tank to discharge through the spout 9 and then as the arm 105 depresses the free end of the push rod 107 its opposite end is disengaged from the piston rod permitting the piston 115 to be returned to normal position and allowing 80 the liquid to flow from the supply tank to the feed tank which is provided with a vent pipe 118. The spout 9 is pivotally connected to the valve 8 and is normally offset from the delivery position shown in dotted line 85 in Figure 3. A push rod connection 119 extends between the spout and the vertical leg 108 of the bell crank 106 for the purpose of swinging the spout into delivery position over the cup as the piston 115 is moved to 90 permit the liquid to flow therethrough. The cup delivery mechanism generally indicated by the numeral 120 is attached to the forward end of the plunger 93 which is carried in a slide block 121 on the transverse member 3, which also carries a pair of inclined rails 122 the purpose of which will appear later. Carried upon the forward end of the plunger 93 is a cylinder 123 in which is fitted a hollow plunger 124 having 100 105 opposed vertical slots 125 in its side walls and an aperture 126 which is adapted to register normally with the core 127 of the plunger 93. A pin 128 is carried in the side walls of the cylinder 123 and extends 110 through the slots 125 which form a guide and also a stop to limit the vertical movement of the plunger 124. A further pin 129 extends through the plunger transversely adjacent its upper end, the ends of 115 which are adapted to ride up the inclined guides and to withdraw the plunger 124 to its elevated position on the completion of the return stroke of the plunger 93.

Extending between the pin 128 and the 120 pin 129 is a tension spring 130 for the purpose of drawing the plunger 124 downwards when released. Extending through the plunger 93 is a spring pressed rod 131 one end of which is adapted to be thrust into 125 the aperture 126 of the plunger 124 to hold it in elevated position during the greater part of the forward stroke of the cup delivery mechanism, and is turned back upon itself at the opposite end as at 132 so as to engage the 130

slide block 121 at the completion of the forward stroke above mentioned to release the plunger 124 and allow it to descend. Mounted upon the upper end of the plunger 124 is a pair of cup arms 133 which are carried upon a pivot pin 134. The cup arms are provided rearwardly of the pin 134 with tongues 135 which are engaged in a pair of slots 136 converging downward which are formed in a vertical plate 137 carried upon the forward end of the plunger 93. It will therefore be seen that the plunger 124 on being released, acting in conjunction with the tongues 135 in the slots 136, will cause the cup arms 133 to spread apart to release the cup and to enable the arms and the cup delivery mechanism to be withdrawn from the delivery recess 100, leaving the filled cup standing therein.

20 The doors 99 are both hinged upon a bolt 138 and are each provided with an outstanding lug 139 adjacent the hinging point. The numeral 140 indicates a short crank upon the main shaft 36 having a pivotally mounted eyed boss or pin 141 at its outer end, through which one end of a spring tensioned push rod 142 extends, the opposite end of the push rod being connected to a crank 143 on a shaft 144, which shaft is provided 25 with a pair of arms 145 which are adapted to engage the lugs 139 of the doors 99 so that, as the forward movement of the shaft 36 takes place, the weight of the doors depresses the arms 145 and pushes the rod 142 30 in an upwardly inclined direction and similarly as the shaft 36 is restored to normal position and the other functions relative to the delivery of the filled cups are completed and also the cup operating mechanism returned 35 to its starting position, the doors are closed by the upward movement of the arms 145 and locked by the locking dogs 98 falling back into place. Simultaneously with these movements the lowermost cup above the cup arms 133 is permitted to fall into position between the arms and upon the cranked arm 32 to put the coin channel section 28 in alignment with the channel 27 so that a further coin may be dropped to again close the motor circuit.

40 The entire mechanism hereinbefore described is obviously enclosed in a casing (not shown) through which access is obtainable to the supply tank and coin receptacle, and is provided with suitable access to the coin receiving and return channels.

45 Having thus described the several parts of my invention and the functions of the various movement I will now describe the co-ordination of those movements.

50 On the motor being started through the closing of the electric circuit by the coin dropped into the channel 27, rotation is imparted to the ratchet wheel 40 and shaft 36 in a clockwise direction (viewing the ma-

chine from the side shown in Figures 1 and 9) until the rocker 38 is released therefrom. During this movement the crank 57 on the shaft 36 through the clutch disc 70 and the mitre pinions 18 and 17 rotates the cup carrier 15 one quarter of a revolution and disposes another column of cups over the cup arms 133 over the cranked arm 32. The lip of the lowermost cup of this column is detached from the one next above it by the turned lip 20 of the thread 14^A, the cup being prevented from falling by the opposite side of the lip being supported on the segment 22. It is desired to point out that on account of the cups being formed to a similar taper and nested together, the lowermost cup of a column may be held in place by being supported at one side of the rim only. Simultaneous with the clockwise movement of the shaft 36 the spout 9 is carried by cam 111 on shaft 36 into delivery position over the cup to be filled, and the valve 8 is operated to discharge the contents of the feed tank 6. When the shaft 36 assumes its final position in a clockwise direction the crank 66 is brought down to trip the coin channel groove 30 to drop the coin and cut off the current from the motor allowing it to come to rest. Since the dog 39 on the ratchet wheel 40 is lifted out of engaging position, the wheel may continue to rotate until the momentum of the motor shaft is being overcome without affecting the operation of the shaft 36. The shaft 36 through its crank 66 is held by the arm 68 against return until the plunger 60 has completed its inward stroke in the dash pot 65. The crank 85 is raised out of contact with the cam 87 so that it is free to rotate under the influence of the spring 75 and against the resistance of the dash pot 88 as soon as the stop 80 is lifted from the outer end of the crank 81. When sufficient time has elapsed for the filling of the cup, the spring tensioned thrust of the rod 60 by the crank 57 has driven the plunger 64 into the dash pot 65 allowing the pin 62 to move the arm 78 and the stub shaft 79 in a clockwise direction. The shaft 79 during this movement swings in a like manner the crank 78, which through the connecting rod 101 and its train of parts, releases the valve plunger 116 allowing it to resume its normal position to shut off the flow to the cup and to open communication from the tank 5 to the feed tank 6 for refilling. The same movement of the crank 78 through the push rod 95 releases the locking dogs 98, so that, as the rod 142 has been released from the downward pressure of the crank 140 and the weight of the arms 145 has caused them to drop, thereby allowing the doors 99 to fall open to the position shown in dotted lines in Figure 5. As the arm 78 is carried to its ultimate clockwise position the tension of the spring 75 imparts clock- 120 125 130

wise rotation to the shaft 77 since the stop 80 has been removed from the crank 81. The arm 68 is drawn back to release the arm 66 on the shaft 36 to permit its being returned 5 in an anti-clockwise direction to its normal position by the falling of the weighted arm 54. As the crank 81 is released the crank 82 withdraws the arm 68 from the pin 67 of the crank 66 freeing the shaft 36 for return or 10 anticlockwise movement under the influence of the weighted lever 54 and the spring 56 at the proper time. The rotation anticlockwise of the shaft 77 which is effected by the spring 75 raises the cam 87 so that the arm 85 may 15 not fall before its appointed time, thus checking the return movement of the shaft 36. This movement also thrusts the cup delivery mechanism forward and carrying the filled cup between the doors 99 when it is 20 deposited in the delivery recess and released. Subsequent to the above movement the influence of the weighted arm 54 in rotating the shaft 36 causes the roller 86 of the crank 85 to bear upon the cam 87 to drive it and 25 the shaft 77 in an anticlockwise direction against the resistance of the dash pot 88, simultaneously withdrawing the cup delivery mechanism from the delivery recess. When the cup arms 133 are clear of the doors 39 30 pressure is applied by the crank 140 of the shaft 36 onto the rod 142 to close the doors. During the final return movement of the shaft 36 the pin 26 on the clutch collar engages the crank 25 of the cup dropping 35 mechanism to permit a cup to fall into position for filling. The final return movement of the shaft 77 permits the latch arm 68 to assume its normal position and disposes the crank 81 into such a position as 40 will allow the shaft 79 to rotate and return the cranks 78 and 94 to starting position. The return of the crank 94 withdraws the push rod 95 and allows the latch 98 to fall into engagement to lock the doors of the delivery recess.

45 What I claim as my invention is:

1. A drink dispensing machine comprising a motive power adapted to be set in motion, a cup delivery recess, having a rear opening, a liquid valve, means for supporting a cup adjacent thereto, means as the motive power is set in motion for discharging liquid into the cup, means for moving the filled cups horizontally through the rear opening into the cup, and for depositing another cup adjacent liquid valve after delivery.

60 2. A drink dispensing machine comprising a casing having a cup delivery recess, a cage in which columns of cups are adapted to be carried, a liquid valve, means for supporting a cup adjacent thereto, means for discharging liquid into the cup from the valve, means for delivering the cup into the recess, and 65 means as the cup is being delivered into the

recess for disposing another column of cups in position for dropping another cup onto the cup support.

3. A drink dispensing machine comprising a casing having a cup delivery recess, a rotatable cage in which columns of nested cups are adapted to be carried, a liquid valve, a cup support adjacent thereto, means for discharging liquid into the cup from the valve, means for delivering the cup from the support to the recess, and means as the cup is being delivered into the recess for imparting rotation to the cage and means as the cup delivery means is withdrawn from the recess for dropping another cup onto the cup support.

70 4. In a drink dispensing machine having a cup filling and delivery means, a rotatable cage in which nested columns of cups are adapted to be carried, said cage being concentrically mounted above a threaded head, a ring having a thread coinciding with the thread of the head, the rims of the cups being adapted to be carried between the opposed threads, and means after a column of 75 cups in the cage makes one complete turn of 80 said threads permitting the lowermost cup of the column to be deposited into position for filling.

85 5. In a drink dispensing machine having a cup filling and delivery means, a rotatable cage in which nested columns of cups are adapted to be carried, said cage being concentrically mounted above a threaded head, a ring having a thread coinciding with the 90 thread of the head, the rims of the cups being adapted to be carried between the opposed threads, means as a column of cups in the cage makes one complete turn of 95 said threads permitting the lowermost cup of the column to be deposited into position for filling.

100 6. In a drink dispensing machine, comprising a casing having a cup delivery recess, means for carrying a column of nested cups, a cup support, a liquid supply valve having a swinging spout normally disposed adjacent the support, means for disposing the spout to deliver liquid to a cup upon the 105 support, and means for subsequently delivering the cup into the cup delivery recess.

110 7. In a drink dispensing machine comprising a casing having a cup delivery recess, means for carrying a column of cups, a liquid supply valve, means for holding a cup to be filled from the valve, means for carrying the filled cup into the cup delivery recess, means for releasing the cup when so delivered and for returning the cup holding 115 means into normal position, and means for depositing an empty cup from the column therein.

120 8. In a drink dispensing machine comprising a casing having a cup delivery recess,

means for carrying a column of cups, a liquid supply valve, means for holding a cup to be filled from the valve, means for carrying the filled cup into the cup delivery recess, means for releasing the cup when so delivered and for returning the cup holding means into normal position, means for depositing an empty cup from the column therein, said cup delivery means comprising 10 a pair of arms adapted to embrace the cup, to spread apart to release the cup after delivery and to close to normal holding position to receive an empty cup.

9. In a drink dispensing machine comprising 15 a casing having a cup delivery recess, a door normally closing entrance to the recess from the casing, means within the casing for carrying a column of nested cups, a cup support, a liquid supply valve, means for 20 filling the cup from the valve, means for opening the recess door and for delivering the filled cup therethrough, means for withdrawing the delivery means into the casing and for closing the door when so withdrawn.

25 10. In a drink dispensing machine com-

prising a casing having a cup delivery recess, a door normally closing entrance to the recess from the casing, means within the casing for carrying a column of nested cups, a cup support, a liquid supply valve, means for 30 filling the cup from the valve, means for opening the recess door and for delivering the filled cup therethrough, means for withdrawing the delivery means into the casing and for closing the door when so withdrawn, 35 and means for locking the door.

11. In a drink dispensing machine comprising 40 a casing and a delivery recess having a cup filling and delivery means, means for carrying a column of nested cups, a cup support, a liquid supply valve adjacent the support, means for opening the valve to fill the cup, and means for closing said valve after a predetermined period, means for delivering the filled cup into the recess, and means 45 for disposing another cup in position to be filled after delivery of the previous one.

Dated at Vancouver, B. C., this 22nd day of June, 1925.

JAMES HOWARD McLELLAN.
